UNITED STATES PATENT OFFICE.

PETER J. BERTUCCI, OF NEW YORK, N. Y.

MUSIC-LEAF TURNER.

1,133,915.

Specification of Letters Patent. Patented Mar. 30, 1915.

Application filed September 19, 1913. Serial No. 790,725.

To all whom it may concern:

Be it known that I, PETER J. BERTUCCI, a citizen of the United States, residing at New York city, in the county of New York and 5 State of New York, have invented new and useful Improvements in Music-Leaf Turners, of which the following is a specification.

This invention relates to music leaf turners particularly adapted for use in connection with pianos and organs, and has for its 10 general object to improve the general character of devices of this sort and to facilitate the operation of the leaf turning arm by the adaptation of a foot controlled mechanism.

15 A further object of the invention is to provide a simple, cheap and efficient device of this character, whereby the operating mechanism is incased within the instrument.

To these ends the invention consists in the 20 novel details of construction and combination of parts more fully hereinafter described and particularly pointed out in the claims.

Referring to the accompanying drawings 25 forming a part of this specification in which like numerals designate like parts in all the views:—Figure 1 is a perspective view of a portion of a piano showing my invention applied thereto. Fig. 2 is a longitudinal 30 sectional view of the parts shown in Fig. 1. Fig. 3 is a horizontal sectional view of the lower part of the same. Fig. 4 is a cross sectional view of the music holder or magazine. Fig. 5 is a detail perspective view of 35 parts of the music leaf turner with portions shown in section.

My improved music leaf turner is preferably adapted for use in connection with pianos and organs and comprises a music 40 holder or magazine 1 having a leaf turning arm 2 to which is connected a suitable foot actuating mechanism 3.

The magazine is preferably formed of thin sheet metal, rests upon the usual ledge 45 4 formed on the musical instrument and comprises the rectangular-shaped body 5 formed to provide a compartment 6 for holding and storing a number of sheets of music. Openings 7 and 8 are provided in 50 the front wall of the magazine through which the music sheets may be seen, and pivotally secured to the dividing partition 9 is a leaf turning arm 10 having spring clips 11 for connecting thereto a sheet of 55 music when the device is in use.

To prevent abrasion of the musical instrument the magazine is provided with feet 12 and a top rest 13 which are suitably covered with a soft material as indicated at 14.

The leaf turning arm may, if desired, be 60 either hand or foot actuated. If foot actuated the magazine member as shown in Fig. 2, has its rod 16 fitted in a socket 18 in which it may be permanently secured if desired. The socket is fitted in a bearing or 65 bushing 19, and is connected to the bevel gear 20 by a universal joint 21. The gear 20 meshes with the bevel gear 22, which by virtue of being formed rigidly with the gear 23, is operated by the gear 24. A rod 25 70 connects the gear 24 with a pinion 26, which engages a segment 27. This segment is provided with ears 28—28 which pivotally hold the rods 29—29. These rods pass through openings 30 in the lower front portion of 75 the instrument and terminate in pedals 31—31. Thus when the segment 27 is operated on the pivot 32 by the pedals 31, the leaf turning member 2 will be turned backwardly or forwardly by means of the series 80 of intervening gears.

It is obvious that those skilled in the art may vary the details of construction and arrangements of parts without departing from the spirit of my invention and therefore I do not wish to be limited to such features except as may be required by the 85 claim.

What is claimed as new is:

A music leaf turner comprising a holder 90 adapted to rest upon a support, an arm journaled upon the holder and disposed in front thereof and having an end portion projecting below the holder, clips carried by the arm, a shaft journaled for rotation, a 95 mechanism adapted to be operated by the foot and operatively connected with the shaft, a universal joint connected with the shaft and a socket member connected with the universal joint and receiving the lower 100 projecting end of the arm.

In testimony whereof I affix my signature in presence of two witnesses.

PETER J. BERTUCCI.

Witnesses:

JOHN A. DONEGAN,
C. JAMES CRONIN.
